UNITED STATES PATENT OFFICE.

DANIEL MENDENHALL, OF FAIRFIELD, IOWA.

IMPROVEMENT IN HAND-LOOMS.

Specification forming part of Letters Patent No. 58,865, dated October 16, 1866.

To all whom it may concern:

Be it known that I, DANIEL MENDENHALL, of Fairfield, Iowa, have invented certain new and useful Improvements in Looms; and I do hereby declare the following to be a full, clear, and exact description of the same, reference being had to the drawings which accompany this specification and form a part of the same, and to the letters of reference marked thereon.

Figure 1 is a perspective view of the rear end of the loom. Fig. 2 is a perspective view of the front end of the same.

In Fig. 1, $a a^1$ is the batten, constructed in the ordinary manner, and hinged to the framing A, near the bottom of the loom. The lever e is hinged to the cross-bar a^2 of the batten, near its center, and extends to and the opposite end rests upon the tappet-cylinder o. To the lever e is attached a jack, i, the catch of which embraces a tappet upon the cylinder o as the batten which carries the lever e is thrown back, and by the return motion of the batten a partial revolution of the tappet-cylinder o is produced.

B is a rod extending across the rear end of the framing, supported by the uprights $c c'$, upon which the ends of the treadles 1 2 3 4 and 1' 2' 3' 4' are secured, four of which are upon each side of the loom immediately above the tappet-cylinder o, the treadles being operated by the action of the tappets s s s s of said cylinder. The front ends of these treadles are each connected with the frames of the heddles E E E E by means of wires or braces $h h h$.

Underneath the tappet-cylinder o are the sub-treadles $x x x x$, corresponding to and parallel with the treadles 1 2 3 4, and arranged at such equal distance below the cylinder o as to be operated by the before-mentioned tappets s s s s. The front ends of these sub-treadles $x x x x$ are connected with the heddle-frames in a like manner as the upper treadles. The action of the tappets upon the upper and sub treadles alternately produces a corresponding motion perpendicularly of the heddle-frames.

L, Fig. 1, is a sliding bracket attached to the upper cross-piece of the batten, working horizontally upon a guide-pin, N, by means of a slot near the upper edge. Immediately underneath and parallel with this slot is an oblong opening, which terminates in angular slots

of a uniform angle above and below, the center of which forms a wedge of the desired angle, terminating in straight sides formed by the continuation of the angular slot in lines parallel to the plane of the bracket. The bracket L works upon the outside of the heddle-frame A', and receives its reciprocating motion from the batten.

The heddle-frames E E E E are each provided with a pin, V, inserted in the outside end of the frame, and working in the oblong square opening of the bracket L.

The operation of this arrangement is as follows: The batten, being against the web, is drawn forward, the jack turning the cylinder o, the tappets of which raise the heddle E sufficiently to bring the pin V above the point of the wedge M, thus partially opening the shed of the warp. As the batten returns, the point of the wedge comes in contact with and raises the pin V, and also the heddle to which it is attached, holding open the shed during that portion of the vibration of the batten till, reaching the point of the wedge again, the pin passes under and another pin has been raised by the tappets and treadles, which is in turn raised and lowered in the same manner.

It will be observed that the full motion of the heddle is produced by the combined movements of the treadles and brackets, as before described.

The operation of the wedge M and the slots with which it is surrounded has a positive and constant action upon the movement of the heddles, holding them or moving them with perfect certainty and precision, as may be requisite.

In Fig. 2, $m m'$ are levers hinged to arms which are framed into the cross-bar a^2 , and extending backward nearly to the rod B. Near their junction with the arms, and forward of the hinges, the lower surfaces of these levers are provided with notches or offsets. Attached to the cross-piece A³, and near its center, is the rocker-arm I, having a semicircular head, H, and held in position by the cap-block H'. The notches in the under side of the levers $m m'$ are intended to operate the head H, as they are operated back and forth by the batten, the tappets n n' raising each alternately, so as to permit the free action of the other.

The picker-staffs F F, placed outside of the

framing, are pivoted at the bottom to the bars G G, and are connected with the rocker-arm I by means of the cords g g, secured in the holes J J. The vibrations given to the rocker-arm I by the action of the levers m m' operate the picker-staffs alternately, giving the requisite force and direction to the shuttle.

In Fig. 1, 5 is a hinged bar, the rear end of which is provided with a pin fitting into suitable holes in the cylinder O as the batten comes forward, while the backward motion of the batten releases it by means of the cross-bar of the batten, which presses upon the same. In the same figure, and operating at nearly the same point upon the cylinder O, is a pawl, 6, which at every partial revolution of the cylinder drops behind a suitable tappet thereon, and secures it in its proper position rigidly.

The lower bar of the heddle-frames may be so constructed as that the wires may be attached to a separate piece, which may be connected or disconnected with the frames at pleasure.

Having thus fully described my said invention, what I claim as new, and desire to secure by Letters Patent, is—

1. The sliding bracket L, with its openings and wedge M, and the pins V V V V, all constructed and operating in the manner and for the purposes set forth.

2. The combination and arrangement of the treadles 1 2 3 4 and the sub-treadles x x x x with the tappet-cylinder O and jack i, as and for the purposes set forth.

3. The hinged levers m m' and tappets n n, in combination with the batten and with the rocker-arm I, head H, cords g g, and picker-staffs F F, said several parts being respectively constructed and the whole arranged for use as described.

DANIEL MENDENHALL.
